UNITED STATES PATENT OFFICE.

CHARLES W. HELD AND RICHARD B. LOCKE, OF BROOKLYN, NEW YORK.

LIFE-GUARD AND TRACK-CLEARER.

SPECIFICATION forming part of Letters Patent No. 293,653, dated February 19, 1884.

Application filed April 7, 1883. (No model.)

To all whom it may concern:

Be it known that we, CHARLES W. HELD and RICHARD B. LOCKE, of Brooklyn, county of Kings, and State of New York, have jointly 5 invented certain new and useful Improvements in Life-Guards and Track-Clearers, of which the following is a full, clear, and exact description, reference being had to the accompanying drawings, and to the letters of reference marked 10 thereon.

Our invention has relation to that class of devices ordinarily employed upon street-cars for the purpose of preventing persons or objects upon the track from being run over by 15 the wheels of the car, obviating danger and damage to the person, as well as keeping the track free of obstruction.

The objects of our invention are to provide a simple, cheap, and durable guard for the 20 wheels and clearer for the track, which may be readily applied upon cars of any ordinary construction, which will, when so applied, be free to move quickly and easily against the car-wheel, (by which the revolving block is 25 turned,) and which will not be likely to become damaged or disarranged during ordinary use.

To accomplish these objects our improvements consist, essentially, in certain novel and 30 useful means of suspending the revolving guards in position with respect to the car-wheels, and certain novel and useful peculiarities in the construction of the guards or revolving blocks, all of which will be herein 35 first fully described, and then pointed out in the claims.

In the accompanying drawings, forming part of this specification, Figure 1 is a side elevation, showing the lower part of a car and 40 our improved life-guards and track-clearers mounted thereon. Fig. 2 is an end elevation, showing the same. Fig. 3 is a plan of the bottom of the car, showing the longitudinal strips inside the wheels, intended to serve as 45 an attachment for the inner hooks or eyes by which the inner arms of the hangers are sustained. Fig. 4 is a sectional elevation, (enlarged,) showing the form and construction of the revolving blocks, and the hangers by 50 which they are suspended from the car-frame.

In all these figures like letters of reference,

wherever they occur, indicate corresponding parts.

The cars to which our improvements are intended to be applied may be of any of the 55 ordinary forms.

A represent the car-wheels mounted upon axles B B. C C are the axle-boxes, upon which the body of the car is mounted, and D D represent the usual exterior string-pieces. In 60 these string-pieces, at suitable intervals with respect to the wheels, we apply the hooks a a, for the reception of the ends of the outside parts of the hangers. These hooks are shown as open to receive the hangers; but obviously 65 they might be made in the form of rings or eyes. They are preferably screwed into the string-piece or other convenient substantial part of the car-frame. The inner sides or ends of the hangers are sustained by similar 70 hooks or eyes applied upon interior string-pieces, E E, or upon any equivalent supports.

F F are the hangers, and G G the revolving blocks or guards. The hangers are each made of a single piece of metal, pass through the 75 blocks to form axles therefor, and are loosely swung in the hooks or eyes, (not so that they will become displaced,) in order that the blocks may ride free and clear of the wheels until struck by any object. When they strike 80 the wheels, they are made to revolve in the opposite direction from the wheels, and thus throw any object from off the track.

The blocks or guards G are preferably made of cast-iron, hollow in order to insure lightness, but of sufficient strength to withstand 85 any ordinary usage to which they may be subjected. The wearing-surfaces of these blocks may be roughened or corrugated in any suitable manner, if desired, in order to insure 90 turning as soon as they are forced against the wheels. Each block has an elongated hub or projecting part, g, to pass by the flange of the car-wheel and allow the exterior surface of the block to strike fairly against the tread of 95 the car-wheel, and also a smaller projection on the opposite side, as at g', in order to keep the block from wearing against the hanger, as it would otherwise do. The hangers may be passed through the hollow blocks and afterward bent to proper shape; or they may be 100 first formed and then placed in the mold and

the blocks cast around them. When the open hooks are employed to sustain the hangers, the latter are simply hooked into place, and if the hooks are deep enough will not be accidentally displaced. Any convenient means of locking them or keeping them in the hooks may be adopted, if required. In case rings or eyes be employed instead of the hooks, then the ends of the hangers may be sprung through the rings or eyes, and will be kept from accidental displacement by reason of their spring power. Side guards to protect the space between the wheels on each side of the car may be made by connecting the hangers on each side by any suitable rods or braces. The improved guards are intended to be applied in front of each of the forward and in rear of each of the rear wheels, and may also be applied between the wheels on each side of the car, if desired.

The construction of the hangers is simple, cheap, and efficient, and they require no alteration of the car in order to apply the guards for work. They may be applied without the use of special tools, and by any ordinary mechanic.

The revolving guards are durable and serviceable, not likely to be damaged or disarranged, amply strong to remove any object from the track, and they may be cheaply made.

The improvements, considered as a whole, will be found to admirably answer all the purposes and objects of the invention as previously set forth.

In former patents granted us on our separate or individual improvements we have shown revolving guards suspended in front of the car-wheels and calculated to revolve as soon as struck by any object and forced up against the tread of the car-wheel.

Having now fully described our invention, what we claim as new, and desire to secure by Letters Patent, is—

1. In a life-guard and track-clearer, the herein-described hanger for the revolving block, the same being made of a bar or rod of metal passing through the block in order to form the axle thereof, extending up on both sides of the block and arranged to be applied upon the car-body and to swing thereon, substantially in the manner and for the purposes set forth. 45

2. In a life-guard and track-clearer, the hanger for the revolving block, made of a bar or rod of iron passing through the block, the hooks or rings for connecting said hanger with the car-body, and the revolving block, all combined and arranged to permit the hanger to swing freely in its supports, substantially 55 60 as shown and described.

3. In a life-guard and track-clearer, the revolving block arranged to swing in front of the car-wheel, the same being cast hollow and admitting the axle, substantially as and for 65 the purposes set forth.

4. The herein-described hollow revolving block or guard, provided with the projecting hub on one side to clear the flange of the car-wheel and another hub or projection on the 70 opposite side to prevent wearing against the hanger, substantially as shown and described.

In testimony that we claim the foregoing we have hereunto set our hands in the presence of two witnesses.

CHAS. W. HELD.
RICH. B. LOCKE.
